UNITED STATES PATENT OFFICE.

JAMES TABB DONAHOO, OF EDGAR, NEBRASKA.

APPARATUS FOR FORMING CEMENT TANKS.

SPECIFICATION forming part of Letters Patent No. 787,157, dated April 11, 1905.

Application filed September 12, 1904. Serial No. 224,157.

To all whom it may concern:

Be it known that I, JAMES TABB DONAHOO, a citizen of the United States, and a resident of Edgar, in the county of Clay and State of Nebraska, have made certain new and useful Improvements in Apparatus for Forming Cement Tanks, of which the following is a specification.

My present invention is an improvement upon that for which I have received Letters Patent No. 744,509. The apparatus is particularly adapted for forming cement tanks of large dimensions or having a high vertical wall.

The details of construction, arrangement, and operation of parts are as hereinafter described, reference being had to the accompanying drawings, in which—

Figure 1 is a perspective view illustrating the main features of the apparatus, portions being broken away to show the interior construction and arrangement of parts. Fig. 2 is a cross-section of the base portion of the apparatus omitting the outer fixed form or wall and also the shaper for the bottom of the tank. Fig. 3 is a vertical section illustrating the connection of certain parts with the lower portion or base of the rotating mast. Fig. 4 is a perspective view illustrating the means for pressing together the planks of the inner cylindrical form. Fig. 5 is a cross-section on line 5—5 of Fig. 1.

The cistern or tank to be produced is circular in form. For producing the same I employ an outer cylinder A, which is fixed in position and constitutes the outer form, while an inner revolving cylinder B constitutes the inner form, between which parts the vertical wall of the completed tank or cistern is produced, the two forms A B being spaced apart the distance corresponding to the required thickness of the side or wall of the tank. In connection with the inner revolving cylinder form B, I employ special means connected with a vertical concentric mast or post C for supporting and carrying said form, and I also employ in connection with said mast a form and revolving shaper D, which forms the bottom of the tank.

I will now proceed to describe the details

of construction and arrangement of parts. The vertical revolving mast or post C is stepped in a base-plate 1 and provided at the top with a tenon 2, which is cylindrical in form and adapted to rotate within an iron cap 3. This cap is connected by guys 4 with stakes 6, driven in the ground at a suitable distance around the fixed cylinder A. It will be understood that the cylinder A is first set in position concentric with the mast or post C and that the same may be conveniently constructed of steel sections held in place by means of bands 7, as shown. The inner cylindrical form B is similarly constructed of vertical steel sections, the same resting and being supported upon a series of connected segmental plates 8, arranged with their sides outward, so as to form a circle corresponding to the diameter of the form B. As shown in Fig. 1, the form B rests in a rabbet or shoulder formed on the outer edge of the segments 8. The latter are connected by metal plates 9, which are secured by screws or nails. Their ends are also attached to radial steel bars 10, whose inner ends enter a circumferential groove in a collar 11, which is fixed on the mast 6 and revolves therewith. The arrangement is further illustrated in Fig. 3. For supporting the parts 8 I employ guys 12, which are provided with turnbuckles, as shown, for the purpose of adjusting their length as conditions require. The upper ends of these guys are secured to a collar 13, applied to the upper portion of the mast C and held in due position thereon by means of cross-bolts 14, (see Fig. 5,) and their lower ends are attached to the eyes of screw-bolts 15, inserted in the segments 8. Hoops 16 are applied to the upper and lower portions of the inner form B, and the upper portion of the same is braced interiorly by means of connected segments 8^a and radial plates or bars 10^a, whose inner ends enter and are adapted to slide around in a grooved collar 11^a. A lever 17 is secured to the top of the mast C and extends laterally, so as to be adapted for use in rotating the mast and therewith the inner form B. It is preferred that the operator shall travel upon a raised scaffold. (Illustrated by dotted lines, Fig. 1.) It is obvious that

two or more levers may be employed, as conditions require. As before stated, the two forms A and B are separated a distance equal to the thickness the completed tank is required 5 to have.

For shaping the bottom portion of the tank I employ a bar D, which preferably consists of an iron tube having its outer end upturned to form the corner of the tank. This shaper 10 D is secured to the bottom of the mast by means of a clamp consisting of clevises 18 and a cross-bar 19, as shown in Figs. 1 and 3. The upturned end of the shaper D abuts the under side of one of the segments 8, and its outer 15 side is of course in alinement with the corresponding side of the inner form B.

It will now be understood that by applying due pressure upon the lever 17 the mast C will be rotated, and that the cylindrical former 20 B, with all its attachments 8, 10, 8^a, 10^a, and 12, will be carried around or revolved, also 25 that the shaper D will have a similar movement and sweep around over the surface upon which the cement is deposited. Such deposit is made in the first instance through the space 30 between the upper braces 10^a and the lower braces 10, and the shaper D passing over the cement smoothes it down and spreads it out until it attains the required thickness and has 35 a smooth surface. In other words, the bottom of the tank reaches the dotted line indicated in Fig. 1. The cement for forming the side wall is of course deposited in the space between the two cylindrical forms A and B, the 40 inner form being left stationary while this portion of the work is being completed. The cement may be tamped while being deposited in order to insure homogeneity of structure. The cement wall will be carried nearly to the 45 top of the forms A B, as indicated by dotted line, Fig. 1.

When the cement has set, the apparatus is removed, leaving the cistern or tank standing.

It is required that the steel sections 45 composing the inner cylinder or form B shall fit tightly together, so that the form as a whole shall have due rigidity, and for this purpose I employ means illustrated in Figs. 1 and 4. The same consists of a plate 20, which is essentially right angular, and devices formed of right-and-left screws and a right-and-left nut 50 21, with which they are connected. One member of the plate 20 is set against the edge of a section 22, as shown, and the other overlaps 55 the opposite one, 23, so as to cover the space that intervenes them, while the adjusting devices 21 are arranged between the section 23 and the radial member of the angular plate 20. It is now apparent that by rotating the 60 nut 21 pressure may be applied to the opposing sections 22 23, and thus to all the sections composing the form B, so that they will be held in close and firm contact.

What I claim is—

1. The improved apparatus for forming cement tanks, comprising an outer cylindrical fixed form, an inner concentric form spaced from the outer one, a mast arranged concentric with the two forms and stepped at its lower end, means for supporting the mast vertically while permitting its free rotation, and means for connecting it with the inner rotatable form whereby the two are operated together, substantially as described. 65

2. The improved apparatus comprising an outer fixed cylindrical form, an inner revolving concentric form spaced therefrom and means for supporting and carrying said inner form which consist of a central rotatable mast, a series of radial braces extending from said 70 mast, segments connecting the outer ends of the same and devices connected with the mast and serving as vertical supports substantially as described. 75

3. The improved apparatus comprising an outer fixed cylindrical form, an inner and concentric form which is spaced therefrom, a central rotatable mast, segments upon which the inner form is supported and carried and guys 80 extending from such segments to the mast and 90 serving as vertical supports substantially as described. 85

4. The improved apparatus comprising two cylindrical concentric forms which are spaced apart, the inner one being adapted to revolve, 95 and concentric rotatable-mast segments and radial braces connected and arranged for supporting and bracing the inner form at its base, a corresponding series of segments and radial braces arranged near the top of the inner 100 form, grooved collars on the rotatable mast which receive the inner ends of the radial braces, and means for supporting the inner form as a whole from the said mast substantially as described. 105

5. The improved apparatus comprising a central vertical mast, a concentric cylindrical form and means for supporting it and carrying it with the mast when rotated, and a support secured to and revolving with the mast, 110 the same extending radially from the latter and having its outer end arranged in working relation with the base of the said form, substantially as described. 115

6. In an apparatus for forming cement tanks the inner revolvable part comprising a cylindrical form, a concentric rotatable mast, means for bracing the said form radially from 120 said mast and devices connected with the base portion of the form and the upper portion of the mast and a shaper attached to the mast substantially as described. 125
